UNITED STATES PATENT OFFICE.

JOHN CALVIN WARREN, OF MENALLEN, PENNSYLVANIA.

UMBRELLA.

SPECIFICATION forming part of Letters Patent No. 376,693, dated January 17, 1888.

Application filed April 27, 1887. Serial No. 236,330. (No model.)

To all whom it may concern:

Be it known that I, JOHN CALVIN WARREN, a citizen of the United States, residing at Menallen, in the county of Adams and State 5 of Pennsylvania, have invented certain new and useful Improvements in Umbrellas; and I do declare the following to be a full, clear, and exact description of the invention, such as will enable others skilled in the art to which 10 it appertains to make and use the same, reference being had to the accompanying drawings, and to letters or figures of reference marked thereon, which form a part of this specification.

15 Figure 1 of the drawings is a representation of this invention, and is a side view of a portion of an umbrella-frame. Fig. 2 is a detail and a top view of the bearing *c* formed on the arm *C*. Fig. 3 is a detail, and is an outside 20 view of a portion of the arm *C*. Fig. 4 is a detail and a side view of the top portion or eye *b* of the arm *C*. Fig. 5 is a side view of a portion of the arm *C*. Fig. 6 is a perspective view of the upper ring-bearing. Fig. 7 is a 25 perspective view of a portion of arm *C*.

This invention has relation to umbrellas; and it consists in the construction and novel combination of parts, all as hereinafter set forth.

30 In the accompanying drawings, the letter *A* designates the stem or staff of the frame, and *B* the upper ring-bearing for the eyes of the arms *C*.

D is the runner, having the flange *E* for the 35 lower eyes of the braces *F*.

The arm *C* is made of steel wire, and its upper end is bent in hook form to pass around the bearing *a* of the ring *B*, and said hook is thus bent to close its end around said bearing 40 to form an eye, *b*, whereby the arm is connected to the upper ring. At the proper distance from this eye *b*, which is in the vertical plane, is formed a transverse eye, *c*, by bending the arm *C* at this point in loop form, as 45 shown, the eye being formed on the inside of the arm and the extensions *e* and *f* of said arm being brought in line with each other by twisting the wire in forming the eye. These arms *C* support the cloth of the umbrella. 50 The braces *F* are formed at the lower ends with hooks *g*, which pass around the bearings

h of the runner-ring and are bent inward to connect to the same after being placed in position. These hooks are usually bent from the inside outward in order to bring the braces 55 close to the stem or staff *A*. At their upper ends the braces are bent in hook form, usually from the outside inward, and are connected in the transverse eyes of the arm *C*. These braces are also made of steel wire. 60

The bearing slot or notch of the upper ring, *B*, is formed with strong parallel walls or edges at the sides of the bearings, as at *v*, adapted to prevent the upper or vertical eye of the arm *C* from turning sidewise. Being 65 braced in vertical position by these walls, the eye holds the arm true, so that the transverse eye at the middle portion of its length is presented inwardly for connection with the upper hook of the brace *F*. The bearings of the 70 runner *D* are formed with parallel guide-walls, as at *v*, at the sides of the bearings, to hold the lower hooks of the braces in outward planes, so that they will work truly with the 75 transverse eyes of the arm *C* and will not give to one side. In this manner is formed an economical and serviceable umbrella, which can be readily and cheaply constructed and repaired, and will be found very durable.

Having described this invention, what I 80 claim, and desire to secure by Letters Patent, is—

An umbrella-frame consisting of the bearing-ring and the runner-ring having the central bearings integral therewith, and forming 85 the parallel guide-walls extending from the four sides of said bearings, and the steel-wire arms *C*, having hooks at their upper ends to engage the bearings in the upper ring, and having the integral transversely-bent eyes at points 90 intermediate of their length for engaging the upper hooks of the braces *F*, the lower ends of said braces being hooked to engage the central integral bearings in the runner, substantially as specified. 95

In testimony whereof I affix my signature in presence of two witnesses.

JOHN CALVIN WARREN.
